DESIGN FOR A SHRINE

William Taylor Jones, Scranton, Pa., assignor to Consolidated Molded Products Corporation,
Scranton, Pa., a corporation of Delaware

Application May 5, 1948, Serial No. 146,173

Term of patent 14 years

(Cl. D29—23)

To all whom it may concern:

Be it known that I, William Taylor Jones, a citizen of the United States, residing at 440 South Main Avenue, Scranton, in the county of Lackawanna and State of Pennsylvania, have invented a certain new, original, and ornamental Design for a Shrine, of which the following is a specification, reference being had to the accompanying drawing forming part thereof.

I claim:

The ornamental design for a shrine, as shown.
WILLIAM TAYLOR JONES.
